(57) **CLAIM**

The ornamental design for a bottle, as shown and described.

DESCRIPTION

FIG. 1 is a front-top perspective view showing a bottle;

FIG. 2 is a back-bottom perspective view of FIG. 1;

FIG. 3 is a left side view of FIG. 1;

FIG. 4 is a right side view of FIG. 1;

FIG. 5 is back side view of FIG. 1;

FIG. 6 is a front side view of FIG. 1;

FIG. 7 is a top side view of FIG. 1; and,

FIG. 8 is a bottom side view of FIG. 1.

The broken lines depict portions of the bottle that form no part of the claimed design.
